[57] CLAIM

The ornamental design for a combined ball-point pen and fan, as shown and described.

DESCRIPTION

FIG. 1 is a front elevational view of a combined ball-point pen and fan showing my new design;

FIG. 2 is a left side elevational view;

FIG. 3 is a rear elevational view;

FIG. 4 is a right side elevational view;

FIG. 5 is a top plan view; and,

FIG. 6 is a bottom plan view thereof.

The fan blades in all views have been shaded to indicate textured surface patterning which is continuous throughout the surfaces thereof.
